FLOOR MAT

Filed June 16, 1922

Inventor
Charles E. Bateman
By Bradbury + Caswell
Attorneys

UNITED STATES PATENT OFFICE.

CHARLES E. BATEMAN, OF MINNEAPOLIS, MINNESOTA.

FLOOR MAT.

Application filed June 16, 1922. Serial No. 568,683.

To all whom it may concern:

Be it known that I, CHARLES E. BATEMAN, a citizen of the United States, residing in Minneapolis, in the county of Hennepin and State of Minnesota, have invented a new and useful Floor Mat, of which the following is a specification.

My invention relates to improvements in floor mats.

- 10 Its object is to provide an improved mat, which is simple and durable in construction, also flexible and reversible, whereby the same is easily handled and maximum wear thereof attained.
- 15 With the foregoing and other objects in view, which will appear in the following description, the invention resides in the novel combination and arrangement of parts and in the details of construction hereinafter described and claimed.

In the drawings, Fig. 1 is a fragmentary plan view of a mat embodying my invention; Fig. 2 is a similar view illustrating a modified form thereof and Fig. 3 is a sectional view in detail, taken on the line 3—3 of Fig. 1.

My improved mat, as will be observed from Fig. 1 of the drawing, includes essentially a plurality of slats 10, links A joining the same and spiral springs 11 between the slats. Said slats 10 are strips of hard wood or other suitable material. Links A, in chains, near the ends of the slats 10 and intermediate thereof hingedly join said slats 35 and lend a flexible character to the mat, whereby the same may be flexed to accord with an irregular supporting surface or turned in a roll for convenience in handling. Each link A comprises a wire shank 12, extending through a transverse bore 13 in a slat, eyes 14 being formed at the extremities of the link by turning the ends back upon said shank. The reversed portions of each link supply opposed abutments 15 between which a slat is secured against slipping. The companion eyes 14 of adjacent links A lie in planes at right angles with respect to each other so that the joints will give freely.

The spiral springs 11 are interposed between the slats 10, the end of each spring being anchored in transverse bores 16 in the same slat.

The springs 11 are greater in diameter than the thickness of the slats 10 so that the opposite sides thereof project beyond the bearing surfaces of said slats. The springs

11 also closely fill the spaces between the slats 10 and serve as spacing elements, which prevent play between the eyes 14 of the links A. Said links A in the intermediate chain 60 or chains have their engaging eyes interlocked with the turns of the springs 11, said association resulting in strengthening the springs against endwise displacement. Supplemental means for securing the springs 11 65 in place upon their respective slats and for additionally strengthening the same against endwise displacement, consist of clips 17 anchored in the slats 10 and overreaching turns of the springs 11. 70

In Fig. 2, the slats 10 are assembled in alternating relation, the springs 11 being arranged in the spaces between said slats. As in the form shown in Fig. 1, these springs function as scraper treads on either side of 75 the mat, the resiliency of said springs permitting of the seating of the slats upon a supporting surface.

A spring 11 may be applied to each slat, if desired, or to certain only of said slats, 80 as shown in Fig. 1, when it is preferred to limit the scraper-tread area.

Changes in the specific form of my invention, as herein disclosed, may be made within the scope of what is claimed without departing from the spirit of my invention. 85

Having described my invention, what I claim as new and desire to protect by Letters Patent is:

1. A floor mat comprising, in combination, a plurality of slats, links hingedly joining said slats together, side by side, spiral springs interposed between the slats and secured thereto, the springs serving as spacing elements for said slats, also as 90 scraper treads, said springs being greater in diameter than the thickness of the slats and functioning in reversed positions of said mat.

2. A flexible, reversible floor mat comprising in combination, a plurality of slats hinged together in parallel relation, spiral springs arranged between certain slats and serving as scraper treads, said springs being greater in diameter than the thickness of the 100 slats and adapted to function in the reversed positions of said mat.

3. A floor mat comprising in combination, a plurality of slats joined together in parallel relation, spiral springs interposed between and secured to certain slats, said 110 springs being greater in diameter than the

thickness of the slats and yieldable to permit the seating of said slats on a supporting surface.

4. A floor mat comprising, in combination, a plurality of slats, spiral springs interposed between the slats, and links joining the slats, certain of said links being interlocked between turns of the springs, the upper sides of said springs lying above the upper surfaces of the slats.

5. In a floor mat, a plurality of slats joined together in spaced relation, spiral springs secured at their ends to and lying between certain slats, said springs being greater in diameter than the thickness of the slats and supplemental means for securing the springs to the slats at points between the ends of said springs.

6. A reversible floor mat comprising, in combination, a plurality of spaced slats and spiral springs mounted on said slats in position between the same, said springs being greater in diameter than the thickness of the slats and serving as scraper treads on either side of said mat.

7. In a floor mat, a plurality of slats and

spiral springs between the slats, the upper sides of said springs lying above the upper surfaces of the slats.

8. A floor mat including a plurality of slats, interlocking eyes joining said slats in parallel relation and spiral springs between the slats supplying scraper treads, also spacing elements preventing play between said eyes.

9. A floor mat including a plurality of slats, links hingedly joining said slats in spaced parallel relation, and spiral springs interposed between and secured to said slats, each link comprising a shank extending transversely through a slat, each end of each shank being turned back to form an eye for engagement with the adjacent eye of the companion link, also to form opposed abutments to prevent longitudinal movement of the link relative to its respective slat, said springs serving as scraper treads and spacer elements to prevent play between the engaging eyes of said links.

In testimony whereof, I have signed my name to this specification.

CHARLES E. BATEMAN.
